UNITED STATES PATENT OFFICE.

THEODORE W. FOSTER, OF PROVIDENCE, RHODE ISLAND.

DESIGN FOR A HANDLE FOR NAIL-FILES, &c.

SPECIFICATION forming part of Design No. 29,262, dated August 23, 1898.

Application filed July 29, 1898. Serial No. 687,219. Term of patent 3½ years.

To all whom it may concern:

Be it known that I, THEODORE W. FOSTER, of Providence, in the county of Providence and State of Rhode Island, have invented and produced a new and original Design for the Handles of Nail-Files and Similar Articles, of which the following is a specification, reference being had to the accompanying drawings, forming part thereof.

- 10 Figure 1 is a front view of the handle, showing my design. Fig. 2 is a side view of the same. Fig. 3 is a sectional view on the line A A of Fig. 1; and Fig. 4, a sectional view on the line B B.
- 15 The leading feature of my design consists in the six-sided tapering form of the handle surmounted with the ornamented head terminating in the faceted disk, as will be more fully set forth hereinafter.
- 20 In the drawings, a indicates a nail-file, to which the handle is secured. A button-hook b is indicated in broken lines. The lower part of the handle is formed into the bulb c, the two opposite sides of which are ornamented with a floral design. From the bulb c the handle gradually enlarges, forming six tapering sides d d, terminating near the upper end in the inwardly-curved leaf ornaments e e, the space between which is ornamented on each side by the pendent floral ornaments ff. 30 The two oppositely-disposed foliated scrolls g g support the seal-shaped knob i, the upper member of which is ornamented by the foliated scrolls K and is surmounted by the faceted disk or jewel l. The handle presents 35 to the eye the appearance of a tapering six-sided ornamental jeweled hilt or handle.

Having thus described my invention, what I claim as new, and desire to secure by Letters Patent, is—40 The design for the handle of a nail-file or similar article substantially as herein shown and described.

In witness whereof I have hereunto set my hand.

THEODORE W. FOSTER.
